UNITED STATES PATENT OFFICE.

MAX HERSKOVITZ, OF CHICAGO, ILLINOIS, ASSIGNOR TO PEERLESS LIGHT COMPANY,
OF CHICAGO, ILLINOIS, A CORPORATION OF MAINE.

ELECTRIC-LIGHT CLUSTER SOCKET.

Application filed July 23, 1918. Serial No. 246,275.

To all whom it may concern:

Be it known that, I, MAX HERSKOVITZ, a citizen of the United States, residing at Chicago, in the county of Cook and State 5 of Illinois, have invented a new and useful Improvement in Electric-Light Cluster Sockets, of which the following is a specification.

My primary object is to provide a novel, 10 simple and economical construction of cluster-socket which may be used in a large variety of ways. Other objects are to provide a cluster-socket which may be caused to assume different positions for causing the electric light bulbs supported thereby to extend 15 upwardly or downwardly, as desired, depending upon the way in which the socket is wired, and to provide a construction which may be used in connection with hanging domes, and in lamps, or the like, involving supporting standards which rise from 20 a base; and other objects as will be apparent from the following description.

Referring to the accompanying drawings—

Figure 1 is a view in side elevation of a cluster socket involving a certain feature of my invention shown as supported from a standard and arranged to cause the lights 30 to incline downwardly. Figure 2 is a similar view showing certain parts in section. Figures 3 and 4 are sections taken at the lines 3 and 4 on Fig. 1 and viewed in the direction of the respective arrows. Figure 5 is a view like Fig. 1 of a cluster-socket 35 adapted to receive the current-conducting wires through either one of opposed portions thereof, the socket being shown as supported on a standard; and Figure 6, a similar 40 view showing the cluster-socket wired from above in suspended condition, as in the case of a hanging dome.

Referring to the construction illustrated in Figs. 1 to 4, inclusive, the cluster-socket 45 is formed primarily of a casing 6, which preferably is hollow and formed of metal, the hollow body thus provided being so shaped as to present socket-housing hollow portions 7 extending generally in opposite 50 directions, but preferably in slightly converging relation, as shown, the casing referred to being formed of sections 8 and 9, with the joint between them extending lengthwise of the portions 7. The section 8 55 is, by preference, the top of the casing 6,

and the section 9 the bottom thereof, these sections being preferably connected by the lap-joints 9^a and by means of screws 10 passing through ears 11 on the section 8 and screwing into the section 9.

The portions 7 of the casing 6, which are open at their extremities, are provided with electric socket-interiors, the terminals of which are to be wired to the electric current-conducting wires which enter the casing 6, the electric socket-interiors employed being formed as unitary structures independently of the casing, and preferably being the socket-interior commonly used with attachments for electric terminals, as distinguished from assembling with the casing 6 a number of separate parts, separately secured to the casing and forming a socket with electrical connections only by reason of their connection with the casing 6, to bear a certain relation to each other.

In the construction shown, the form of socket-interior employed is of a well-known type in which switching mechanism operated as by the pull-chain 12, is self-contained. The portions 7 of the casing 6 are shaped generally to conform to the contour of the socket-interiors and the latter are preferably surrounded by linings 13 of insulating material located in the portions 7 of the casing, there being provided on the interior of the casing, adjacent the inner ends of the socket-interiors, lugs 14 which abut against the inner ends of the socket-interiors and aid in rigidly holding them in position in the casing 6.

In the assembling of the parts of the cluster-socket illustrated, the electric light socket-interiors, with the insulated linings 13 surrounding them, are laid into the lower portions of the ends of the casing 6, with the electric current-conducting wires, which have been preliminarily secured to the terminals of the socket-interiors, extending within the casing, these wires in the particular construction illustrated extending upwardly through the base or standard 16 which supports the cluster-socket, as, for example, in the case of a table lamp. The top section 8 of the casing is then applied to the bottom section 9 thereof and firmly secured in position by the screws 10, the sections 8 and 9 preferably clamping relatively tightly against the linings 13 to aid in preventing rotation of the socket-interiors in the

the casing, it being preferred that in addition thereto screws 10^a screw into the casing-section 9 and into the socket-interiors to insure a rigid connection between the casing and socket-interiors.

The casing 6 is apertured at its lower portion as indicated at 17 at which it screws upon the upper threaded end of the standard 16, and its upper portion, by preference, carries an upwardly-extending lug 17^a containing an upwardly-extending screw 18 secured as by the solder represented at 19, and adapted to engage top-knob 20 which screws thereon, the construction just referred to presenting a means whereby a lamp shade (not shown) may be secured to the casing 6, the shade fitting over the screw 18 and being held down against the lug by the knob 20.

20 The cluster-socket portions of the structures illustrated in Figs. 5 and 6 are the same as those shown in the preceding figures, except that the lug portion of the section 8, and represented at 21, contains a screw-threaded opening 22 opening into the interior of the casing 6. This opening is provided to adapt the casing 6 to receive the electric current-conducting wires through either of opposed openings in the casing, 25 namely, either through the opening 22 or 17, as desired, which adapts the casing to be supported from a standard, as in the case of a table lamp as shown in Fig. 5, with the electric current-conducting wires extending 30 upwardly through the standard, as explained of the construction shown in Figs. 1 and 2, in which case the opening 22 would preferably be plugged, as by the threaded knob 23, or supported with the lamps extending in an upwardly inclined direction 35 by connecting the casing 6 at its opening 22 with the standard 16; or by supporting the casing 6 from a depending element, as, for example, a chain represented at 24, with the lamps downwardly inclined, by screwing the eye 25 having a hollow stem 26 into the opening 22 and leading the wires downwardly through this opening into the casing 5, or by inverting the casing 6 and screwing the eye 25 into the opening 17, in which case the lamps would incline upwardly, in either 40 of the last two cases referred to a knob, such as that represented at 27, being screwed into the one of the openings in the casing 45 which is not used for leading the wires into the latter.

It will be understood from the foregoing that a cluster-lamp socket constructed in accordance with my invention is of simple construction and may be economically and readily manufactured, and when provided with openings in opposed portions of the casing thereof for leading the wires into the casing

may be used in many different combinations and to support lamps in varying position.

While the socket-interiors referred to are provided with switch mechanism for separately controlling the lamps in the sockets, it will be understood that if desired socket-interiors without switching mechanism may be employed and the switch or switches for the same be located at any desired point, and, if desired, a single switching device of any desirable type, may be employed within the casing 6 for controlling both sockets.

What I claim as new and desire to secure by Letters Patent is—

1. A cluster-lamp socket formed of a hollow body having outwardly and downwardly extending portions and divided longitudinally into two parts, unitary pull chain sockets located in the outwardly extending portions between the parts, means for holding the parts together, and means for introducing electrical conductors.

2. A cluster-lamp socket formed of a hollow body presenting outwardly-extending hollow portions, and electric-lamp-receiving socket-portions formed as unitary structures independently of said body, located within said hollow portions, said body containing openings in opposed portions thereof adjacent the inner ends of said hollow portions, adapting current-conducting wires to extend into said body from either side for electrical connection with said sockets.

3. A cluster-lamp socket formed of a hollow body presenting outwardly-extending portions and formed of sections with the joint therebetween extending lengthwise of said hollow portions, and electric-lamp-receiving socket-interiors formed as unitary structures independently of said body, located within said hollow portions, said body containing openings in opposed portions thereof adjacent the inner ends of said hollow portions, adapting current-conducting wires to extend into said body from either side for electrical connection with said sockets.

4. A cluster-lamp socket formed of a hollow body presenting outwardly-extending portions and formed of sections with the joint therebetween extending lengthwise of said hollow portions, and electric-lamp-receiving socket-interiors formed as unitary structures independently of said body and located within said hollow portions, the interior of said hollow member being so shaped as to adapt the socket-interiors wired to each other to be introduced into one of the sections of said hollow member through its open side, to extend into said hollow portions of said member.

MAX HERSKOVITZ.
